FOLDING IRON

Edward J. Fitzgerald, Winsted, Conn., assignor to
 Son-Chief Electrics, Incorporated, Winsted,
 Conn., a corporation of Connecticut

Application November 18, 1943, Serial No. 510,794

3 Claims. (Cl. 219—25)

The instant invention relates to flatirons and more particularly to an electric flatiron having a hinged or foldable handle so as to facilitate packing the iron into a small space as when traveling or in packaging the same.

One of the primary objects of the invention is the construction of a flatiron of the type indicated with the handle hinged at its rear end and unsupported at its front end, the operative support for the handle being a lever pivoted forwardly of the pin of the handle hinge.

Still another aim is the manufacture of a flatiron as specified above in which the lever is held in place and the handle in operative position by the plug of the appliance cord, so that both the lever and handle are capable of pivotal movement only upon removal of the plug.

Yet another purpose is the making of a flatiron which is of low, flat design; which is efficient in use, and formed of but few parts and is relatively cheap to manufacture.

The above and other aims and objects will be apparent from the detailed description herein-after appearing when taken in conjunction with the appended drawings showing a preferred embodiment of the invention and in which

Fig. 1 is a side elevational view, partly broken away, showing the flatiron with an appliance plug operatively connected thereto and the iron handle in operative position for use;

Fig. 2 is a top plan view of the structure of Figure 1;

Fig. 3 is a sectional view taken on line 3—3 of Figure 1;

Fig. 4 is a perspective view of the locking lever;

Fig. 5 is an elevational view similar to Figure 1, but with the appliance plug removed, the locking lever in inoperative position, and the handle folded to rest on the base;

Fig. 6 is a view similar to Fig. 5 but showing another position the locking lever may assume;

Fig. 7 is a sectional view taken on line 7—7 of Figure 6; and

Fig. 8 is a fragmentary top plan view of the appliance plug socket and the seat for the head of the locking lever.

The electric iron is generally designated as A and comprises as its essential features a relatively flat base B, a handle H, hinged to the base and a pivoted locking lever L. Base B may be made of separable upper and lower flanged plates 10 and 11, respectively, said plates being appropriately shaped and forming a pocket therebetween to receive the electric resistance coils for heating the iron in a manner forming no part

of the instant invention. The handle H is solid and as conventional is made of some insulating material such as wood, plastic or the like and comprises a forward portion 12, a lower or under portion 13 having an undulating surface 14 forming spaced recesses 15 for receiving the fingers of the hand of the user to afford a firm gripping area when the handle is grasped. Rear portion 16 of the handle is outwardly flared and enlarged as at 17 and has an angularly disposed flat base 18. Secured to the latter is one plate 19 of a hinge 20 having a horizontally disposed hinge pin 21, the other plate 22 of hinge 20 being fixed to the upper surface of plate 10 adjacent the rear end thereof. It will now be understood that handle H is capable of pivotal movement toward and away from base B about hinge pin 21 as an axis.

Locking lever L, as best seen in Figs. 3 and 4, includes a supporting base comprising a horizontal plate member 23 having a pair of spaced ears 24, 25 extending vertically from the opposed sides thereof. The lever proper designated as 26 is a substantially rectangular plate and has a pair of opposed pintles 27, 28, pivotally supported in ears 24, 25, respectively, of lever base 23.

Adjacent the upper end thereof lever 26 is provided with a pair of inwardly extending opposed notches 29, 30 and a forwardly projecting semi-circular head 31, all for a purpose to be shortly described. A nut-equipped threaded stud 32 in base 23 operatively secures locking lever L to base plate 10 just forwardly of hinge 20 as will be clearly seen in Figs. 1, 5 and 6.

Enlarged rear portion 16 of the handle H has a vertical through opening or socket 33 and a curved wall portion 34 partially defining said socket, the latter being of a size and shape to receive the electric appliance plug 35 at one end of a current-carrying cord 36 adapted to be connected to a current outlet in the usual manner. Portion 16 is further cut away forwardly of opening 33 as at 37, the latter having a seat 38 near the upper portion thereof, and seat 38 comprising a pair of inwardly extending spaced ledges 39 and 40, slightly below the upper surface of the handle, see Figure 3.

In the operative position of the flatiron A, the lever 26 is inserted into the plug opening or socket 33 and swung forwardly or to the left as seen in Figure 1 on pintles 27 and 28 to receive the ledges 39 and 40 in notches 29 and 30 thereof, respectively, whereby head 31 of the lever 26 will be positioned in the depressed seat 38, and the handle H supported by the lever in the position

shown in Figure 1. When plug 36 is inserted into socket 33 the lever 26 will be inhibited from swinging rearwardly and the handle will remain in proper operative position for use of the electric iron so long as the plug is not removed.

Upon withdrawal of the plug from socket 33, however, lever 26 may be swung rearwardly to assume the position shown in Figure 5 whereby the forward portion 12 of handle H will swing downwardly on its hinge and rest on base plate 10. The flatiron A will now occupy a smaller space and is in condition for packaging or for insertion into a travelling bag or the like. In the position of the lever shown in Figure 5, the head 31 of said lever prevents handle H from swinging about its hinge. In Figure 6 there is shown another position which lever 26 may assume.

From the above, it will be apparent that there has been disclosed and described an electric flatiron fully commensurate with the various aims and objects hereinbefore set forth. Although the description is detailed, changes in the specific features will be apparent to those skilled in the art, and it is contemplated to cover all such and to be limited in this respect as may be necessary by the scope of the claims hereto appended.

What I claim and desire to secure by Letters Patent is:

1. An electric flatiron comprising a base adapted to contain a heating coil, a handle hinged to said base adjacent one end thereof, said handle having an appliance plug receiving socket at its hinged end, a locking lever for said handle pivoted to the base and extending into said socket, said lever being immovably held in said socket upon insertion of the appliance plug into the latter.
2. An electric flatiron comprising a base, a handle having a plug-receiving socket hinged to said base, a pivoted locking lever for said handle extending into said socket, said handle and lever being immovable upon insertion of said plug within said socket.
3. An electric flatiron comprising a base, a handle having a plug-receiving socket hinged to said base, a pivoted locking lever for said handle extending into said socket to hold said handle in operative position, said handle being locked in the latter position upon insertion of said plug within said socket.

EDWARD J. FITZGERALD.
